EXTENSION LADDER

Merton Smith, Cleveland, Ohio, assignor, by
mesne assignments, to McCabe-Powers Auto
Body Co., St. Louis, Mo., a corporation of
Missouri

Application March 24, 1949, Serial No. 83,191

2 Claims. (Cl. 254—148)

1

This invention relates to an extension ladder provided with means for readily effecting the extension of one section with reference to the other. The object of the invention is to provide not only simple means for effecting the extension but also means for readily controlling the descent of the extendable portion by gravity, so that there will be no danger of injuring the operator or damaging the apparatus. My extension ladder is well adapted for mounting in any suitable manner as for example on a vehicle where it may lie in a horizontal position for transportation and be raised into an inclined or approximately vertical position for use.

The invention is illustrated in the drawing hereof and hereinafter fully explained and the essential novel features are summarized in the claims.

In the drawings, Fig. 1 is a side elevation of my extension ladder indicated as mounted on a vehicle, part of which is shown; Fig. 2 is a fragmentary elevation on a larger scale of the ladder in a plane transverse to Fig. 1; Fig. 3 is a side elevation of mechanism for controlling the extension; Fig. 4 is a cross section through the elevating mechanism, in a plane indicated by the line 4—4 on Fig. 3; Fig. 5 is a fragmentary sectional elevation on a larger scale of a portion of the operating mechanism shown in Fig. 4.

The base portion of my extension ladder indicated at 10 in Figs. 1 and 2 comprises a pair of parallel side bars and various cross bars 11. The extension member 12 also has a pair of parallel side bars connected by cross bars 13. The side bars of the extension are slidably connected, as by tongue and groove or other suitable means, with the side members of the base 10.

I have indicated the base 10 as mounted on suitable supporting mechanism carried by a standard 20 rising from a vehicle 21. The supporting mechanism indicated in general at 22 is not shown in detail as it constitutes no portion of the present invention. It may be constructed in accordance with Patent No. 2,422,507, issued June 17, 1947 to my assignee, The American Coach & Body Company, as assignee of Herman J. Troche and Elton J. Farrar.

To effect the extension of the ladder member 12 along and beyond the member 10, I provide a cable 30 anchored at its upper end to the upper portion of the base ladder 10 as, for instance, by looping around a top cross rod 11 of the base ladder. This cable then extends along the extension ladder to the lower portion thereof where it passes around two pulleys 31 carried by brack-

2

ets 32 extending inwardly from the side bars of the extension ladder. The cable then passes upwardly to a pulley 33 and also secured to the uppermost cross bar 11 and thence downwardly to a winding drum 40 carried by the base member 10.

The winding drum 40, shown in detail in Fig. 4, comprises a hollow barrel 41 and two disc heads 42 and 43. These heads are tightly mounted on a rotary shaft 45 journaled in bearings 46 and 47 carried by brackets 56 and 57 respectively. The brackets in turn are carried by the side members of the base ladder 10. I have shown a collar 48 welded to the head 42 and keyed to the shaft 45 so that the drum is locked to the shaft to rotate therewith while allowing the shaft to be shifted slightly longitudinally thereof, as indicated by the broken lines in Fig. 4 for a purpose hereinafter described. A suitable disc crank 50 slidably keyed to the shaft, furnishes means for rotating the shaft and drum to wind in the cable 30 and thus cause the extension of the ladder 12.

Between the hub of the disc crank 50 and the bearing 47 I mount a distance sleeve 51. Threaded on the shaft on the outer side of the hub of the disc crank is a hand wheel 53 which bears against the hub. A cotter pin or other suitable stop 55 prevents inadvertent removal of the hand wheel 53 from the shaft. Secured to the inner face of the bracket 57 is a rub disc 58 with which the drum head 43 may be caused to contact by a slight lateral shifting of the drum.

Fig. 4 shows in full lines the drum and shaft in position with the drum head 43 in snug engagement with the friction disc 58, which is the braking or lowering position. This view indicates in broken lines the position of the drum and shaft during the raising operation.

In the operation of my invention, the rotating of the hand crank rotates the shaft 45, the hand wheel 53, the shaft 45 and the drum as a unit to wind in the cable to raise the extension. When the extension is descending by gravity the same is controlled by the hand wheel 53, which, being turned manually on the screw thread of the shaft, operates to pull the shaft outwardly and thereby shift the drum slidably toward the hand wheel causing retarding friction between the head 43 and the rub disc 58 on the bracket 57.

The friction, produced by the braking disc may, if desired, be sufficient to firmly hold the extension member elevated or it may be such that the extension gradually and slowly slides down with- 55 in the base ladder.

A suitable gravity latch (not shown) may if desired be applied to the extension ladder to overhang successive rungs of the base ladder and hold it positively in any elevated position which may be given to it, until the latch is manually thrown to idle position preceding the descent.

It will be seen that my elevating mechanism is very simple in construction, readily operated to effect the extension desired without requiring much force by the operator on the handle 59 of the disc crank. During such elevation the shaft and drum rotate freely without binding friction. On the descent of the ladder the mere turning of the hand wheel 53 controls descent so that the ladder may gradually return to its initial position without danger to the operator or causing damage to the mechanism.

I claim:

1. The combination of a base, a member to be raised, a pair of bearings carried by the base, a shaft rotatably mounted in said bearings, a drum between the bearings secured to the shaft, a cable connecting the drum and said member, a hand crank keyed to the shaft in a manner to allow some movement between them axially of the shaft, a member threaded on the shaft and bearing against the hub of the hand crank, means to resist axial movement of the hand crank toward the adjacent bearing, and a friction device between such adjacent bearing and the adjacent end of the drum adapted to coact with the drum when the shaft is shifted axially.

2. The combination of a base, a member to be raised, said base having a pair of bearings, a shaft rotatably mounted in said bearings, a drum between the bearings tightly keyed to the shaft, a cable wound on the drum and leading to said member over a pulley carried by the base, a crank keyed to the shaft in a manner to allow axial movement of the shaft through the crank, a distance sleeve between the hub of the crank and the adjacent bearing, a hand wheel threaded on the shaft and bearing against the outer side of the hub of the crank, and a friction disc between such adjacent bearing and the adjacent end of the drum, adapted to frictionally clamp the drum to the bearing when the shaft is shifted by the hand wheel.

MERTON SMITH.
